UNITED STATES PATENT OFFICE.

GEORGE H. RUMKE, OF DENVER, COLORADO.

AMUSEMENT DEVICE.

1,191,477.

Specification of Letters Patent. Patented July 18, 1916.

Application filed January 25, 1916. Serial No. 74,096.

To all whom it may concern:

Be it known that I, GEORGE H. RUMKE, a citizen of the United States, residing at Denver, in the county of Denver and State 5 of Colorado, have invented certain new and useful Improvements in Amusement Devices, of which the following is a specification.

This invention relates to amusement devices, and its primary object resides in providing a trackway for bicycles or motor-driven vehicles, the continuity of which is interrupted by a vacant space or gap across which a vehicle driven along the riding surface, may leap by the force of its momentum.

In order to prevent the vehicle from moving into the gap, especially on curvilinear tracks, I provide at the forward edge of the 20 same an inclined approach which directs the vehicle toward the portion of the driving surface at the opposite side of the gap.

In the accompanying drawings in the various views of which like parts are similarly 25 designated, Figure 1 is a plan view of a motordrome having an annular driving surface, Fig. 2, a similar view of a similar motor-drome showing a modified construction of the approach, and Fig. 3, a vertical section taken along the line 3—3, Fig. 1.

Referring to Figs. 1 and 3 of the drawings the reference character 2 designates a bowl-shaped motordrome, the driving surface of which is composed of a cylindrical, 35 axially upright major portion 3 and an inwardly slanting minor portion 4 which connects the main trackway with the floor 5 of the structure and provides a surface along which a vehicle circling within the motor- 40 drome, ascends.

The main riding surface has adjacent its upper edge, a gap 6, and at the edge of the gap forward with relation to the direction in which the vehicle moves along the track, 45 an inclined approach 7 which projects inwardly from the cylindrical surface.

It will be readily understood that a vehicle circling the driving surface at a high velocity, will when driven over the edge of

the approach, leap through space and across 50 the gap by the force of its momentum and continue its course upon engaging the driving surface at the opposite side of the gap.

In the form shown in Fig. 1, the approach inclines gradually in a curved line 55 from the surface of the trackway, forward of the gap, while in the construction illustrated in Fig. 2, the surface of the approach is straight and its deviation from the driving surface more abrupt.

It will be understood that the improved trackway may be made in forms other than those shown in the drawings and that the approach instead of being made of a separate block fastened upon the trackway, may 60 be formed by curving the driveway itself inwardly in front of the gap, or by any other suitable method.

Having thus described my invention what I claim and desire to secure by Letters-Pat- 70 ent is:

1. In an amusement device, an annular riding-surface surrounding a vertical axis, and a gap interrupting the continuity of 75 said surface.

2. In an amusement device, an annular riding-surface surrounding a vertical axis, a gap interrupting the continuity of said surface, and an approach inclined from said surface toward said gap and terminating 80 adjacent the forward edge of the same.

3. In an amusement device, an annular riding-surface surrounding a vertical axis, a gap interrupting the continuity of said surface, and a curved approach inclined 85 from said surface toward said gap and terminating adjacent the forward edge of the same.

4. In an amusement device, an annular riding surface surrounding a vertical axis 90 and comprising a continuous portion and adjacent thereto a portion the continuity of which is interrupted by a gap.

5. In an amusement device an annular riding surface surrounding a vertical axis 95 and comprising a lower continuous portion and an upper portion the continuity of which is interrupted by a gap.

6. A motordrome having an internal annular riding surface and a surface extending inwardly continuous with the first-mentioned surface at one of its ends and spaced 5 from the same at its opposite end.

7. A motordrome having an internal annular riding surface surrounding a vertical axis, and a surface extending inwardly continuous with the first mentioned surface at

one of its ends and spaced from the same at 10 its opposite end.

In testimony whereof I have affixed my signature in presence of two witnesses.

GEORGE H. RUMKE.

Witnesses:

G. J. ROLLANDET,
L. RHOADES.
